UNITED STATES PATENT OFFICE

147,030

DESIGN FOR A BUTTON OR SIMILAR ARTICLE

Marion Weeber, New York, N. Y.

Application November 12, 1946, Serial No. 134,697

Term of patent 3½ years

(Cl. D17—2)

To all whom it may concern:

Be it known that I, Marion Weeber, a citizen of the United States of America, residing in New York city, county of New York, and State of New York, have invented a new, original, and ornamental Design for a Button or Similar Article, of which the following is a specification, reference being had to the accompanying drawing, forming part thereof, wherein,

The characteristic features of my design reside in the portions shown in solid lines.

I claim:

The ornamental design for a button or similar article, substantially as shown and described.

MARION WEEBER.
